(57) **CLAIM**

The ornamental design for a solar lighting fixture, as shown and described.

DESCRIPTION

FIG. 1 is a front, left side perspective view of a solar lighting fixture showing my new design;

FIG. 2 is a top plan view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is an alternate front elevational view thereof showing the front at a different angle than that shown in FIG. 3.
